HYDRAULICALLY SET, RELEASEABLE WELL
PACKER
Chudleigh B. Cochran, Houston, Tex., assignor to
Cicero C. Brown, Houston, Tex.
Filed Oct. 9, 1961, Ser. No. 143,686
10 Claims. (Cl. 166—187)

This invention relates to well packers for use in the operation of oil wells, and more particularly to a well packer which is designed to be set by hydraulic pressure and which may be easily released by mechanical manipulation of a tubing string.

In the operation of oil wells, it is frequently desirable to be able to isolate formations located at different depths to permit the same to be separately produced. Under some conditions it is also desirable to provide means by which production may be carried on selectively from any of a number of locations at different levels in a well.

The present invention has for an important object the provision of a well packer which is designed to be applied to a tubing string for insertion therewith in a well casing and which is operable by the pressure of fluid in the tubing to pack off the annulus between the tubing and casing at a desired location.

Another object of the invention is to provide well packer mechanism which is operable by the application of pressure fluid to a well tubing to set the packer and which is operable by rotational movement of the tubing to release the packer.

A further object of the invention is the provision in a well packer of seal forming means of improved construction which is designed to obtain an increased pressure holding force under the influence of a smaller expanding or setting force than has been possible heretofore with the use of seal forming means of the usual type.

Another object of the invention is to provide well packer mechanism embodying a number of packers connected into a tubing string at longitudinally spaced intervals and having means for setting the packers by the introduction of fluid under pressure into the string and means whereby the packers may be independently released as desired by mechanical manipulation of the string.

A further object of the invention is the provision of well packer mechanism which is designed to be set by fluid pressure and including means for releasably holding the packer in a set condition independently of the pressure which is applied to set the same.

Another object of the invention is the provision in well packer mechanism of improved seal forming means in an annulus between a well tubing and a casing surrounding the same for expansion into sealing contact with the tubing and casing to pack off the annulus and embodying a central, radially inwardly tapering seal element, and upper and lower radially outwardly bevelled seal elements above and below said central element, in position for coaction with said central element to form oppositely directed seal forming cups upon setting of the packer by relative longitudinal movement of the elements.

In many well installations it is desirable to set a plurality of packers in a pipe string in order to seal off the well bore between several different producing horizons. In such installations it is often desirable and necessary to initially connect the lower end of the pipe carrying such a string of packer into a permanently set bottom packer previously placed in the well bore, and to thereafter release the string from the bottom packer to adjust the total length of the pipe string before hanging the latter in the well head. Release from the bottom packer

2

is conventionally effected by right-hand rotation of the pipe string but this cannot be accomplished with pipe strings employing the more conventional types of packers without setting the packers or after the packers have been set.

Accordingly, it is an additional important object of this invention to provide a packer structure which permits rotation of the pipe string without setting the packers and which when the packers have been set is operative by right-hand rotation of the pipe string to successively release the packers and extend rotation of the pipe string through its full length to the bottom packer.

A further additional object is the provision of a fluid pressure actuatable packer structure employing a novel form of clutch mechanism between the supporting pipe string and packer body which is releasable by the setting of the packer to release the pipe string for rotation relative to the packer body whereby to release the packer and to transfer the releasing rotation downwardly successively to other similar packers mounted in the pipe string.

In fluid pressure actuated packers, it is desirable to provide means to prevent reverse slippage or retraction of the packers when they have been set, as may often occur due to jarring of the pipe string or reversals in pressure differentials across the packers. Some prior art arrangements have employed small internal slips mounted between the packer compression members or cones and the packer mandrel which are urged into wedging engagement by springs to effect the desired anchoring function. However, these spring-urged slips have proved unsatisfactory in that often they will slip back under the forces to which they are subjected, the springs employed being ineffective to drive the slip teeth sufficiently strongly into the mandrel surface to effectively oppose the unseating forces.

Accordingly, it is a further important object in accordance with this invention to provide an anti-retraction mechanism for packers which is actuated by fluid-pressure.

A more specific object is the provision of a fluid pressure actuated anchor mechanism, for the purpose indicated, employing a plurality of toothed wedge slips and a positive drive means therefor actuated by fluid pressure which may be the fluid pressure employed in setting the packer itself.

A still further object of the invention is to provide well packer mechanism of the type referred to which is of strong and rugged construction and in which the parts are easily replaceable for purposes of maintenance and repair.

The above and other important objects and advantages of the invention will be apparent from the following detailed description, constituting a specification of the invention when taken with the annexed drawings, wherein—

FIGURE 1 is a fragmentary, side elevation view, partly in cross-section showing a portion of a well with a well casing and tubing string therein and illustrating a preferred embodiment of the packer of the invention in released condition prior to the setting of the packer in the well;

FIGURE 2 is a view similar to that of FIGURE 1 illustrating the packer of the invention in set position;

FIGURE 3 is a view similar to that of FIGURE 2 showing the packer of the invention after releasing of the same;

FIGURE 4 is a cross-sectional view, taken along the line 4—4 of FIGURE 1, looking in the direction indicated by the arrows;

FIGURE 5 is a cross-sectional view, taken along the line 5—5 of FIGURE 1, looking in the direction indicated by the arrows; and

FIGURE 6 is a cross-sectional view, taken along the

line 6—6 of FIGURE 1, looking in the direction indicated by the arrows.

Referring now to the drawings in greater detail, the well packer of the invention is illustrated in connection with its use in a well bore having the usual casing C, which may extend to any desired depth in the well, and may be suitably perforated at locations to permit the production of oil or gas from various formations at different depths in the well.

The well packer arrangement of the invention includes one or more packer assemblies, generally designated P, which are connected into a well tubing, generally designated T, for insertion therewith into the casing to be expanded therein to pack off the annulus A, between the casing and tubing at locations to permit the production of the well from any desired formation therein. It will be understood that such packer assemblies will be interspersed with conventional sleeve valves (not shown) by which communication may be established between the tubing and any selected producing formation.

Each of the packer assemblies comprises an inner tubular body or mandrel 10, whose lower end is externally threaded, as indicated at 12, for threadable connection with the upper, internally threaded end of a lower section 14 of the tubing T, and whose upper end is externally threaded, as indicated at 16, for the connection thereto of an internally threaded collar 18, which may be additionally secured to the mandrel by suitable means, such as a set screw 20.

The upper end of the mandrel 10 extends into a coupling formed in two threadably connected parts 22 and 24, the part 22 being internally threaded at its upper end, as indicated at 26, for connection to the externally threaded lower end of an upper section 28 of the tubing T, and internally threaded at its lower end, as indicated at 30, for connection to the part 24. The mandrel 10 is provided with external, coarse threads 32, near its upper end, and the part 24 is similarly provided with internal, coarse threads whereby the mandrel is connected to the tubing T through the coupling. The mandrel is thus connected into and becomes a part of the tubing string.

At its lower end the part 24 is provided with circumferentially spaced, external projections 34, between which internal, circumferentially spaced projections 36 on an upper back-up ring or upper abutment member 38 are slidably received to form a clutch connecting the ring to the part 24 for rotation therewith. The clutch is releasably held in its engaged position by suitable means such as the shear pins 40. The mandrel 10 is also formed with external, longitudinal grooves 42, into which the inner ends of screw-pins 44, carried by the back-up ring 38 are slidably extended to hold the back-up ring against rotation relative to the mandrel.

A lower back-up ring or lower abutment member 46 surrounds the mandrel 10 in longitudinally spaced relation thereon below the upper back-up ring, and an external sleeve 48 is attached at its upper end to the lower back-up ring, as by means of set screws 47, and extends downwardly therefrom in radially outwardly spaced relation to the mandrel to form an annular chamber 50 surrounding the mandrel.

The sleeve 48 is closed at its lower end by an annular member 52 surrounding and attached to the mandrel 10, which extends upwardly within the sleeve. The member 52 is connected to the mandrel for longitudinal movement therewith, by suitable means, such as the internal split lock rings 54 and 55 which fit into suitable annular recesses provided for the same in the mandrel and member. The sleeve 48 is slidable on the member 52 and is releasably connected thereto, as by means of shear pins 56. Suitable seal forming means, such as the O-rings 58 and 59, are provided to form fluid-tight seals, respectively, between the mandrel and member 52 and between the member and sleeve 48.

The lower back-up ring 46 is internally bevelled to form

a downwardly opening, annular, tapered recess 60, within which externally toothed arcuate wedges 64 are slidably received. These wedges normally project slightly below the lower end of the lower back-up ring. Within the chamber 50 an annular piston 66 is slidably disposed in surrounding relation to the mandrel 10 and is provided with suitable seal forming means, such as the O-rings 68, to form fluid-tight seals between the mandrel and piston and between the piston and sleeve 48. The piston 66 is engageable directly with the wedges 64 to move the wedges upwardly in the recess 60 upon upward movement of the piston in the chamber 50 to force the wedge teeth tightly into the external surface of mandrel 10.

The mandrel has a port 70 leading from the interior of the mandrel into the chamber 50 beneath the piston 66 and through which fluid under pressure in the tubing string may enter the chamber 50 to move the piston 66 upwardly.

Between the upper and lower back-up rings 38 and 46, upper and lower annular, expansible packer elements 72 and 74 surround the mandrel 10 and between these elements a central, expansible annular, wedge shaped packer element 76 is located. The packer element 76 tapers radially inwardly and the upper and lower elements 72 and 74 are each formed with a radially bevelled face positioned for engagement with one of the tapered faces of the central element 76, so that when the assembly of packer elements is subjected to longitudinal compression between the upper and lower back-up rings, the elements will be compressed into sealing contact with the mandrel and well casing to seal off the annulus therebetween. During such endwise or longitudinal compression of the packer elements, the elements 72 and 74 are compressed against the tapering faces of the central element 76 to form two oppositely directed cup like portions which open away from each other, as seen in FIGURE 2, whereby fluid is prevented from becoming trapped between the elements.

The coupling part 22 has a port 78 leading from the annulus A into the interior of the tubing string and suitable packing means, such as that shown at 80, surrounds the upper end of the mandrel 10 between the lower end of the collar 18 and a ring 82 surrounding the mandrel 10 in longitudinally spaced relation therebelow. The packing 80 is positioned to close the port 78 against the inflow of fluid therethrough into the tubing T from the annulus A during the insertion of the packer assembly into the well and the setting of the packer in the well casing, as shown in FIGURES 1 and 2, and to open the port 78 to such inflow when the packer is released, as shown in FIGURE 3.

The packer mechanism of the invention is set by the pressure of fluid in the tubing T, and for this purpose suitable means, such as a ball or other similar device, indicated by the dotted line 84 in FIGURE 2, is inserted in the upper end of the tubing, and allowed to move downwardly therein into closing engagement with an internal seat, not shown, in the tubing located below the lowermost one of the packer assemblies, to close the tubing against the downward flow of fluid therethrough.

In making use of the invention, constructed as described above, the tubing T is lowered into the well bore with one or more of the packer assemblies connected into the tubing string at longitudinally spaced intervals, according to the locations of the formations in the well from which it may be desired to produce the well, the packer assemblies being in their released condition, and the clutches 34, 36 engaged, as illustrated in FIGURE 1. In this position of the parts it will be seen that when desirable for whatever purpose in running the string, the entire string of pipe carrying the packers may be rotated without setting the packers.

As previously noted, such rotation may be desirable to release the string from a bottom packer into which the string has been connected for the purpose of adjust-

ing the length of the string before re-connecting the bottom packer and hanging in the tubing head. Thereafter, when the tubing string has been thus inserted in the well and set to the desired depth, the ball 84 is dropped through the bore of the string to close the string at a location beneath the lowermost of the packer assemblies, and pressure fluid is pumped downwardly into the tubing string to set the packers.

During the setting of the packers, fluid under pressure in the tubing string may enter the chamber 50 of each packer assembly through the port 70 thereof, to move the lower pack-up ring 46 upwardly, to compress the packer elements 72, 74 and 76 longitudinally, the set-screws 56 being sheared by such pressure to allow the lower back-up ring and sleeve 48 to move upwardly. During such expansion of the packer, the annular piston 66 will also be moved upwardly in the chamber 50 into direct engagement with the wedges 64, to positively force the wedges into the recess 60 in engagement with the inside tapering face of the lower back-up ring, as illustrated in FIGURE 2, the wedges being thus forced strongly into gripping engagement with the external surface of the mandrel 10 to hold the back-up ring against downward movement, whereby the packer elements will be held in their expanded condition to pack off the annulus between the tubing and the casing at the desired location. During the expanding of the packer, shear pins 40 of the upper back-up ring will also be sheared to allow the upper back-up ring to move upwardly relative to the lower part 24 of the coupling, so that the clutch elements 34 and 36 will be disengaged, as shown in FIGURE 2.

With the packer assemblies thus set in the well casing, the packers may be released successively downwardly in the well, beginning with the uppermost packer assembly by rotating the tubing T, when it is desired to select any particular formation from which the well is to be produced.

During such rotation of the tubing with the packers set, the clutch elements 34 and 36 will be out of engagement so that the lower part 24 of the coupling will be rotated with the tubing and the external coarse threads 32 of the mandrel in engagement with the internal coarse threads of the coupling part 24 will cause the upper back-up ring 38 to move upwardly relative to the mandrel to allow the packer elements 72, 74 and 76 to relax, thus releasing the packer. Upon releasing the packer, the coupling part 22 will be moved to a position to uncover the port 78, so that the hydrostatic head in the tubing will be relieved by the inflow of fluid from the annulus A into the interior of the tubing.

Upon releasing the uppermost packer mechanism in the manner described above, the part 24 of the coupling will move to its uppermost limit on the coarse threads 32 of the mandrel, so that when the packer is released, the entire assembly may be rotated with the tubing T to operate the tubing to release the next lower packer assembly in the same manner. In this manner, the packers may be successively released downwardly in the casing.

It is to be noted that during the setting of the packer mechanism, the radially inwardly tapering faces of the central element 76 will engage the adjacent tapering faces of the elements 72 and 74, so that as the packer is compressed, any fluid entrapped between the elements may escape longitudinally along the external surface of the mandrel and the internal surface of the casing, thus preventing interference of any such fluid with the effective sealing of the packer.

It will thus be seen that the invention, constructed and operated as described above, provides packer mechanism which is easily connected into an operating string of well tubing for insertion therewith into a well bore to be set therein at any desired depth, which is hydraulically operable to set the packer, and which may be readily released by rotation of the tubing string.

The invention is disclosed herein in connection with a

certain specific embodiment of the same, but it will be understood that this is intended by way of illustration only and that numerous changes can be made in the construction and arrangement of the various parts, within the spirit of the invention and the scope of the appended claims.

Having thus clearly shown and described the invention, what is claimed as new and desired to secure by Letters Patent is:

1. In a well packer, a tubing string, a tubular mandrel, thread means forming a rotatable connection between the mandrel and an upper section of the tubing string to cause relative longitudinal movement of the mandrel and said section upon rotation of the section relative to the mandrel, longitudinally spaced back-up rings surrounding and movable longitudinally on the mandrel, expandible packer means surrounding the mandrel between said rings, releasable means for holding one of said rings against movement relative to said mandrel, and pressure fluid actuated means movably positioned on the mandrel to urge the other of said rings toward said one ring in response to the pressure of fluid in the string.
2. In a well packer, a tubing string, a tubular mandrel, means connecting the lower end of the mandrel to a lower section of the tubing string for rotation with said lower section, thread means forming a rotatable connection between the mandrel and an upper section of the string to cause relative longitudinal movement of the mandrel and said upper section upon rotation of the upper section relative to the mandrel, releasable clutch means for causing the mandrel to rotate with said upper section, longitudinally spaced back-up rings surrounding and movable longitudinally on the mandrel, expandible packer means surrounding the mandrel between said rings, pressure fluid actuated means movably positioned on the mandrel to urge said lower ring upwardly in response to the pressure of fluid in the string, means forming a connection between said upper ring and said releasable clutch means to hold the upper ring stationary during upward movement of said lower ring to apply a compressive force to the packer means to expand the packer means and to release said releasable clutch means when the packer means is expanded, said upper ring being movable upwardly upon rotation of the upper section relative to said mandrel to allow the packer means to contract.
3. In a well packer a tubing string, means forming an expandible chamber surrounding and in fluid flow communication with the interior of the string, a movable back-up ring surrounding the string and connected to said chamber means for longitudinal movement on the string upon expansion of the chamber and having an internal annular bevelled face positioned to form with the external surface of the string a tapered recess surrounding the string, a stationary back-up ring around the string in longitudinally spaced relation to said movable ring, wedge means movably mounted on the string for movement into a position in wedging engagement with the string and movable ring in said recess to hold the movable ring against movement away from the stationary ring, means movably disposed in the chamber to move the wedge means to wedging position in response to the pressure of fluid in the string, and expandible packer means surrounding the string between said rings.
4. In a well packer a tubing string adapted to be inserted in a well bore, a sleeve member surrounding the string in radially outwardly spaced relation thereto, stationary means surrounding the string and closing one end of the sleeve member, a movable ring surrounding the string closing the other end of the sleeve member and movable therewith, said stationary means, sleeve member and ring forming with the external surface of the string a longitudinally expansible pressure fluid chamber, said ring having an internal bevelled face positioned to form with the external surface of the string a tapered recess opening into said chamber, wedge means movably dis-

posed in the recess for movement into wedging engagement with the ring and string to hold the ring against movement in a direction to contract the chamber, means for admitting fluid under pressure from the interior of the string into the chamber, means movably disposed in the chamber to move the wedge means to wedging position in response to the pressure of fluid in the string, a stationary ring on the string spaced longitudinally from said movable ring, and expansible packer means around the string in position for engagement with said rings to apply a compressive force to the packer means to expand the packer means into sealing engagement with the string and the surrounding wall of a well bore upon expansion of said chamber.

5. In a well packer, a tubing string, a tubular mandrel, thread means forming a rotatable connection between the mandrel and an upper section of the tubing string to cause relative longitudinal movement of the mandrel and said section upon rotation of the section relative to the mandrel, a sleeve member surrounding the mandrel in radially outwardly spaced relation thereto, stationary means surrounding the mandrel and closing one end of the sleeve member, a movable ring surrounding the mandrel movable with and closing the other end of the sleeve member, said stationary means, sleeve member and movable ring forming with the external surface of the mandrel a longitudinally expansible pressure fluid chamber, said ring having an internal, bevelled face positioned to form with the external surface of the mandrel a tapered recess opening into the chamber, wedge means movably disposed in the recess for movement into wedging engagement with the mandrel and ring to hold the ring against movement in a direction to contract the chamber, means for admitting fluid under pressure from the interior of the mandrel into said chamber to expand the chamber, means movably disposed in the chamber to urge the wedge means toward wedging position in response to the pressure of fluid in the mandrel, a second ring movably mounted on the mandrel in longitudinally spaced relation to the first ring, means connecting said second ring to said connection to hold the second ring against movement away from said first ring in one relative longitudinal position of the mandrel and said upper section and to allow such movement of said second ring in another relative longitudinal position of said mandrel and said upper section.

6. In a well packer, a tubing string, a tubular mandrel, thread means forming a rotatable connection between the mandrel and an upper section of the tubing string to cause relative longitudinal movement of the mandrel and said section upon rotation of said section relative to the mandrel, longitudinally spaced back-up rings surrounding and movable longitudinally on the mandrel, expansible packer means surrounding the mandrel between said rings, releasable means for initially holding one of said rings against movement relative to the mandrel, pressure fluid actuated means having fluid pressure communication with the bore of the mandrel and positioned on the mandrel to urge said other ring toward said one ring and to release said releasable means in response to the pressure of fluid in the mandrel, said rotatable connection including clutch means releasably connecting said upper section of the tubing string to said one of said back-up rings, said clutch means being releasable by said movement of said other ring toward said one ring to release said upper section for rotation relative to said mandrel.

7. In a well packer including a tubular mandrel, longitudinally spaced upper and lower abutment members surrounding the mandrel, the lower abutment member being movable longitudinally of the mandrel toward the upper abutment member, an annular seal element disposed about the mandrel for endwise compression between the abutment members to radially expand the seal element, means for preventing retraction of the

10 seal element, comprising, wedge-shaped anchor elements disposed between the interior of the lower abutment member and the exterior of the mandrel, and pressure fluid actuated means movably mounted on the mandrel cooperating with said anchor elements to urge the same into wedging engagement between the lower abutment member and the mandrel, means for directing actuating pressure fluid from the interior of the mandrel to said last-mentioned means.

15 8. In a well packer, a tubular mandrel, an annular upper abutment member disposed about the mandrel, an annular lower abutment member disposed about the mandrel for longitudinal movement thereon relative to the upper abutment member, an annular seal element disposed about the mandrel between said abutment members, said seal element being radially expansible by endwise compression between said abutment members, pressure fluid actuated means having fluid pressure communication with the bore of the mandrel positioned on the mandrel to urge said lower abutment member toward the upper abutment member to expand said seal element, wedge-shaped anchor elements disposed between the interior of the lower abutment member and the exterior of the mandrel and having portions projecting below said lower abutment member, said pressure fluid actuated means including movable means directly engageable with said projecting portions of the anchor elements to urge the latter into wedging engagement between said lower abutment member and the mandrel to prevent retraction of said seal element.

20 9. In a well packer including a tubular mandrel, longitudinally spaced upper and lower abutment members surrounding the mandrel, the lower abutment member being movable longitudinally of the mandrel toward the upper abutment member, an annular seal element disposed about the mandrel for endwise compression between the abutment members to radially expand the seal element, means for preventing retraction of the seal element, comprising, wedge-shaped anchor elements disposed between the interior of the lower abutment member and the exterior of the mandrel, and pressure fluid actuated means movably mounted on the mandrel cooperating with said anchor elements to urge the same into wedging engagement between the lower abutment member and the mandrel, means for directing actuating pressure fluid from the interior of the mandrel to said last-mentioned means, said annular seal element comprising upper and lower longitudinally spaced annular expansible seal rings having opposed radially inwardly converging end surfaces and outer end surfaces engaged by the respective abutment members, and a central annular expansible seal ring positioned between and having inwardly converging end faces positioned for engagement with the converging inner end surfaces of said upper and lower seal rings.

25 10. In a well packer, a tubular mandrel, an annular upper abutment member disposed about the mandrel, an annular lower abutment member disposed about the mandrel for longitudinal movement thereon relative to the upper abutment member, an annular seal element disposed about the mandrel between said abutment members, said seal element being radially expansible by endwise compression between said abutment members, pressure fluid actuated means having fluid pressure communication with the bore of the mandrel positioned on the mandrel to urge said lower abutment member toward the upper abutment member to expand said seal element, wedge-shaped anchor elements disposed between the interior of the lower abutment member and the exterior of the mandrel and having portions projecting below said lower abutment member, said pressure fluid actuated means including movable means directly engageable with said projecting portions of the anchor elements to urge the latter into wedging engagement between said lower abutment member and the mandrel to prevent retraction

of said seal element, said annular seal element comprising upper and lower longitudinal spaced annular expansible seal rings having opposed radially inwardly converging end surfaces and outer end surfaces engaged by the respective abutment members, and a central annular 5 expansible seal ring positioned between and having inwardly converging end faces positioned for engagement with the converging inner end surfaces of said upper and lower seal rings.
